ELECTRIC IMPACT AND INTERRUPTER
SWITCH APPARATUSRoy H. Smith, Canton, Ohio, assignor of one
fourth to Hurxthal F. Frease, Canton, Ohio

Application March 30, 1940, Serial No. 327,062

14 Claims. (Cl. 172—126)

My invention relates generally to electric impact apparatus which may include a solenoid coil, a hammer such as a plunger arranged for oscillation as by straight line reciprocation by alternate energizing and de-energizing of the solenoid coil, and a switch for controlling the energizing and de-energizing of the solenoid coil by a suitable source of electric power.

Such electric impact apparatus may be included for example in a toy machine gun where it is only desired to simulate the sound of a machine gun, or in a toy or other machine gun wherein it is desired to actually fire caps or bullets, or in an electric reciprocating plunger tool such as an electric hammer, a rock drill, and the like.

In the usual electric reciprocating plunger apparatus, the frequency of reciprocation of the plunger is constant, whereas in a usual air hammer or rock drill, the reciprocations or strokes of the plunger or piston have a variable frequency.

The frequency of reciprocations or strokes of the plunger of a usual electric reciprocating plunger apparatus is controlled by a vibrator or interrupter not only having a constant frequency but also a frequency which is greater than that of the shots of a usual machine gun, and greater than the frequency desired in many cases for the reciprocations or strokes of the plunger of a reciprocating plunger hammer, drill, and the like.

More particularly my invention relates to electric impact and interrupter switch apparatus. Prior to the present improvements the usual electric interrupter has operated at a constant frequency of circuit make-and-breaks, and there has not been available a manually controlled variable frequency electric interrupter switch for use for example for the remote control of electric reciprocating plunger apparatus such as a heavy machine gun, a heavy electric hammer, rock drill, or crusher, and the like.

The objects of the present invention include in general the provision of an improved electric impact and interrupter switch apparatus which may be embodied in an electric reciprocating plunger apparatus having a frequency of plunger reciprocations or strokes substantially the same as the frequency of fire of a usual machine gun, or the frequency of plunger or piston reciprocations or strokes of a usual air hammer, rock drill, or the like.

Further objects of the present invention include the provision of an improved electric im-

pact and interrupter switch apparatus in which the frequency of successive impacts or strokes may be varied.

Further objects of the present invention include the provision of an improved electric impact and the interrupter switch apparatus including improved trigger means for controlling and varying the oscillations or straight line reciprocations or strokes of a hammer such as a plunger.

Further objects of the present invention include the provision of improved manually controlled electric impact and interrupter switch apparatus which may be adapted while operating to provide controlled and variable frequencies of electric circuit make-and-breaks.

The foregoing and other objects are attained by the electric impact and interrupter switch apparatus, parts, combinations, and sub-combinations, which comprise the present invention, the nature of which is set forth in the following general statement, and preferred embodiments of which together with their mode of use are set forth by way of example in the following description, and which are particularly and distinctly pointed out and set forth in the appended claims forming part hereof.

The nature of the present invention may be stated in general terms as including in electric impact and interrupter switch apparatus, a frame, a hammer such as a reciprocating plunger operable to effect successive impacts against the frame, means including an electro-magnetic coil for operating the hammer to effect the successive impacts against the frame, switch means on the frame including two adjacent contacts, means operatively mounting one of the contacts for vibration from and to connection with the other contact by the successive impacts of the hammer against the frame, conductors for connecting the contacts and the coil in circuit with a source of electric power, and preferably trigger means operable to connect and disconnect the contacts.

The nature of the present invention also may be stated in general terms as including in controlled and preferably variable frequency electric impact and interrupter switch apparatus, a frame, controlled frequency means for subjecting the frame to vibration by successive impacts, switch means on the frame for interrupting the current in an electric circuit in accordance with the frequency of the impacts against the frame, the switch means including two adjacent contacts, and means operatively mounting one of the con-

tacts for vibration from and to connection with the other contact by vibration of the frame.

By way of example, embodiments of the improved electric impact and interrupter switch apparatus are illustrated in the accompanying drawings forming part hereof, in which

Figure 1 is a perspective view of a first embodiment of the invention in the form of a toy machine gun having a self-contained flash light battery source of electric power, and being adapted for use to simulate only the sound of a machine gun;

Fig. 2, an enlarged side elevation view of the toy machine gun of Fig. 1 with portions removed, broken away, and shown in section, and the switch contacts being shown disconnected;

Fig. 3, a fragmentary view similar to Fig. 2, the switch contacts being shown connected;

Fig. 4, a perspective view of a second embodiment of the invention in the form of a toy machine gun adapted for operation by connection with a usual electric power line, and which is arranged not only for simulating the sound of a machine gun, but also for firing percussion caps;

Fig. 5, an enlarged side elevation view of the toy machine gun of Fig. 4 with portions removed, broken away, and shown in section, the switch contacts being shown disconnected;

Fig. 6, a side elevation view of a third embodiment of the invention in the form of an electric hammer, with portions removed, broken away, and shown in section, and looking in the direction of the arrows 6-6, Fig. 7;

Fig. 7, another side elevation view of the electric hammer of Fig. 6, with portions removed, broken away, and shown in section, and looking in the direction of the arrows 7-7, Fig. 6;

Fig. 8, a fragmentary side elevation of a fourth embodiment of the invention in the form of another electric hammer, with portions removed, broken away, and shown in section; and

Fig. 9, a side elevation view of a fifth embodiment of the invention in the form of a controlled and variable frequency electric impact interrupter switch for use for example for the remote control and the variable frequency energizing and deenergizing of an electro-magnetic solenoid coil which may be a part of an electric machine gun, a heavy electric hammer, and the like.

Similar numerals refer to similar parts throughout the several views.

In Figs. 1 to 3 inclusive is illustrated a first embodiment of the invention in the form of a toy machine gun indicated generally by 10, and which may be more broadly termed an electric impact and interrupter switch apparatus.

The toy machine gun electric impact and interrupter switch apparatus 10 includes a frame indicated generally by 11 which as shown includes a stock 12 made of wood and an anvil member 13 made of metal secured to the stock 12.

The stock 12 includes a forward downwardly depending handle 14 having a compartment 15 formed therein, the upper end of which is closed by the anvil member 13 in the form of a metal plate or strip. At the forward end of the stock 12 beyond the handle 14 there is secured a tube or rod 16 simulating the barrel of a machine gun, and on top of the plate anvil member 13 there is secured a circular disk 17 with radially arranged mock cartridges 18 secured on its upper side, simulating the magazine of a machine gun.

In the compartment 15 of the handle 14, a metal guide tube 19 is located with its longi-

tudinal axis perpendicular to the anvil plate member 13, and an oscillatable hammer in the form of a straight line reciprocating iron or steel plunger 20 is located for reciprocation in the bore of the guide tube 19.

The lower end of the guide tube 19 is provided with a closure 21 and a rebound helical coil spring 22 is located in the tube 19 below the plunger 20 with the lower end of the spring 22 abutting the tube closure 21, and as shown there is also located a felt silencer plug 23 between the upper end of the rebound spring 22 and the lower end of the plunger 20.

An electro-magnetic solenoid coil 24 is located in the compartment 15 and engirdles the upper end of the guide tube 19 with the reciprocating plunger 20 slidably therein.

The wood stock 12 of the frame 11 also has formed therein intermediate its ends a compartment 25. Improved preferably trigger controlled switch arm and contact means indicated generally by 26 are located in the compartment 25 and include an insulating block B at the upper end of the compartment 25.

From the insulating block B two side by side binding posts 27 and 28 depend downwardly into the compartment 25. A first preferably spring switch arm 29 of conducting material is secured at its upper end to the block B for pivoting or 30 swinging about one axis as shown formed by a bend in the upper end of the arm 29, the bent extremity of the upper end of the arm being secured to the binding posts 27. A second preferably spring switch arm 30 of conducting material is located in the compartment 25 at the forward side of the first arm 29 and the second arm 30 is secured at its upper end to the block B for swinging or pivoting about a second axis as shown formed by a bend in the upper end of the arm 30, the bent extremity of the upper end of the arm 30 being secured to the binding post 28, and the second axis of pivoting being thus spaced at one side of the first axis of pivoting.

A first contact 31 is located on the lower end 45 portion of the first arm 29 on its side opposite the second arm 30, and a second contact 32 is located on the lower end portion of the second arm 30 on the side thereof opposite the first arm 29, and the first contact 31 and the second contact 32 are thus located adjacent and opposite each other.

The forward side of the switch arm and contact compartment 23 has a trigger arm opening 33 formed therein in which is located a trigger arm 34, the upper end of which is pivotally mounted on the stock 12 as by a pivot pin 35. From the rear side of the trigger arm 34 a cam finger 36 extends towards the second switch arm 30, and spring means normally maintain the trigger arm 34 and its cam finger 36 away from the second arm 30, which spring means as shown include a flat spring 37 secured at its upper end to the insulating block 26 and depending downwardly therefrom between the trigger arm 34 and its cam finger 36 and the second arm 30.

As shown a push finger 38 is secured to and insulated from the second arm 30 on its side opposite the flat spring 37 and the cam finger 36 of the trigger arm 34.

Both the push finger 38 and the cam finger 36 are offset from the second contact 32 in the longitudinal direction of the second arm 30.

In the stock 12 at the rear of the switch compartment 23 there is formed a battery compartment 39 having located at its forward end spaced

spring contact strips 40 and 41 and at its rear end a corrugated spring contact strip 42.

Four flash-light dry batteries 43 are located in the compartment 39 in two rows of two end series connected batteries, the lower row of batteries being series connected between the forward spring contact strip 40 and one side of the rear spring contact strip 42, and the upper row of batteries being series connected between the other side of the rear contact strip 42 and the forward spring contact strip 41 whereby the four batteries are series connected between the spring contact strips 40 and 41 and constitute a self-contained source of electric power for the toy machine gun electric impact and interrupter switch apparatus 10.

The battery compartment 39 communicates with the coil compartment 15 by a conduit 44 formed in the stock 12, the conduit 44 communicating intermediate its ends by a branch conduit 45 with the switch arm and contact compartment 25. The battery compartment 39 also communicates with the switch arm and contact compartment 25 by a conduit 46 formed in the stock 12.

A conductor 47 extending through the conduit 44 connects the spring contact strip 41 with one terminal of the solenoid coil 24, and a conductor 48 extending through the conduit 44 and the branch conduit 45 connects the other terminal of the solenoid coil 24 with the binding post 28, and a conductor 49 extending through the conduit 46 connects the binding post 27 with the spring contact strip 40.

At the lower end of the first switch arm 29 there is preferably secured an inertia mass 50 which may be a metal disk.

In the operation of the toy machine gun electric impact and interrupter switch apparatus 10, when the trigger arm 34 is pulled backwards it bows the flat spring 37 as shown in Fig. 3 towards and against push finger 38 on the second arm 30 and moves the second arm 30 and second contact 32 towards the first arm 29. The inertia mass or pendulum disk 50 together with the preferred spring material of the first arm 29 constitutes means urging the first arm 29 to the equilibrium position with respect to the frame 11 shown in Figs. 2 and 3.

When the second contact 32 connects with the first contact 31 as shown in Fig. 3, the series circuit of the contacts 32 and 31, the batteries 43, the solenoid coil 24, and the connecting conductors is closed, and the solenoid 24 is energized causing an up-stroke of the hammer plunger 20 and an audible impact of its upper end against the anvil member 13 of the frame 11.

The impact of the hammer plunger 20 against the anvil member 13 of the frame 11 jars the first arm 29 away from the second arm 30 and disconnects the contacts 31 and 32 and causes the hammer plunger 20 to drop away from the anvil member 13.

The first arm 29 then swings back towards its equilibrium position completing one vibration from and towards its equilibrium position and again connects the first contact 31 with the second contact 32 causing another impact of the hammer plunger 20 against the frame anvil member 13 and another vibration of the arm 29 and its contact 31. Successive impacts of the hammer plunger 20 against the frame anvil member 13 and vibrations of the arm 29 and contact 31 are similarly produced as long as the trigger arm 34 is pulled to push the second spring arm 30

away from its equilibrium position shown in Fig. 1 to a position permitting the vibrating first contact 31 on the vibrating arm 29 to effect successive connections and disconnections of the contacts 31 and 32.

The frequency of the connections and disconnections of the contacts 31 and 32 and thus of the impacts to which the frame 11 is subjected by the reciprocating hammer plunger 20 and thus of the vibrating arm 29 is determined by the extent of pull on the trigger arm 34 which may be varied for producing a variable frequency of reciprocations of the hammer plunger 20 and of the impacts thereof against the frame anvil member 13 and of the vibrations of the arm 29 and contact 31.

In the toy machine gun electric impact and interrupter switch apparatus 10 gravity is utilized to return the hammer plunger 20 away from the anvil member 13. Likewise gravity operating upon the inertia mass or pendulum disk 50 is utilized in part to urge the vibrating arm 29 towards its equilibrium position.

In Figs. 4 and 5 there is illustrated a second embodiment of the invention in the form of a toy machine gun electric impact and interrupter switch apparatus indicated generally by 110 and which is adapted for being energized by connection with a usual household electric power line, that is a 110 volt 60 cycle alternating current line.

The toy machine gun electric impact and interrupter switch apparatus 110 includes a frame 111 which is arranged for horizontal pivoting on the upper end of an arm 151, and the arm 151 is arranged for vertically pivoting on the upper end of a base 152.

A gun barrel simulating tube 116 is located at the forward end of the frame 111 and a guide tube 119 is at the rear of and coaxial with the gun barrel simulating tube 116, and a reciprocating plunger hammer 120 operates in the guide tube 119, and a solenoid coil 124 engirdles the guide tube 119.

Opposite the rear end of the plunger hammer 120, the frame 111 includes a metal anvil member 113.

The rear end of the guide tube 119 is supported in a rear guide tube mounting bracket 153 on the frame 111 and the front end of the guide tube 119 is supported on a front guide tube mounting bracket 154 on the frame 111.

The rear end portion of the plunger hammer 120 extends through a compression coil spring 155, and the rear end of the compression coil spring 155 is secured to the plunger hammer 120 and the forward end of the compression coil spring 155 abuts the rear guide tube mounting bracket 153.

When the solenoid coil 124 is energized the plunger hammer 120 is drawn forward from its position shown in Fig. 5, loading the spring 155, and when the solenoid coil 124 is deenergized the spring 155 thrusts the plunger hammer 120 to impact against the metal anvil member 113.

A coil tape 156 of percussion caps is operatively mounted in the frame 111 and is adapted for being fed downwardly between the anvil member 113 and the rear end of the plunger hammer 120 as by push arm means indicated generally by 157, whereby the caps in the tape 156 may be fired as they pass between the rear end of the plunger hammer 120 as it successively impacts against the anvil member 113.

The toy machine gun electric impact and interrupter switch apparatus 110 furthermore includes improved trigger controlled switch arm and contact means 126 and conductors connecting the same with the solenoid coil 124 and adapted for connection with a household power supply line, and which are substantially the same as the similar trigger controlled switch arm and contact means 26 of the toy machine gun electric impact and interrupter switch apparatus 10 and the conductors connecting the same with the solenoid coil 24 and its flash light battery source of electric power.

Likewise the operation of the toy machine gun electric impact and interrupter switch apparatus 110 is substantially the same as the operation of the toy machine gun electric impact and interrupter switch apparatus 10, with the additional ability of the apparatus 110 to fire the caps in the tape 156.

It is to be noted however that the apparatus 110 only operates on alternating current, the de-energizing of the solenoid coil 124 being first effected after energizing when the alternating current passes through zero and when the loaded spring 155 impacts the plunger hammer 120 against the anvil member 113.

A third embodiment of the invention is illustrated in Figs. 6 and 7 in the form of an electric hammer indicated generally by 210 which also may be more broadly termed an electric impact and interrupter switch apparatus. The electric hammer 210 includes a frame indicated generally by 211 including a cylindric housing 212 in which is located a metal guide tube 219, and a steel plunger hammer 220 is operable in the guide tube 219 for reciprocation between a rebound anvil member 213-1 at one end of the tube 219 and a tool shank guide sleeve anvil member 213-2 at the other end of the tube 219.

The frame 211 also includes a handle 258 on its end where the anvil member 213-1 is located, and at the other end the tool shank guide sleeve anvil member 213-2 is adapted for receiving the shank of a drill and the like which extends beyond the inner end of the sleeve anvil member 213-2 for being struck by the plunger hammer 220, and the inner end of the sleeve anvil member 213-2 constitutes a limiting stop for the plunger hammer 220 in its strokes towards the sleeve anvil member 213-2, whether or not a tool is inserted in the sleeve anvil member 213-2.

Spaced solenoid coils 224-1 and 224-2 encircle opposite end portions of the guide tube 219 and serve by alternate energization and de-energization to reciprocate the plunger hammer 220 in the tube 219 to alternately impact directly the anvil member 213-1 and directly and indirectly the anvil member 213-2.

A control handle 259 is pivotally mounted on one side of the cylindric housing 212 as by a pivot bolt 260 and the control handle 259 may as shown include a body 261 of insulating material with a removable outer cover plate 262.

Within the body 261 of the control handle 259 there is formed a compartment 225 in which are located trigger controlled switch arm and contact means indicated generally by 226.

The switch arm and contact means 226 include within the compartment 225 a first preferably spring switch arm 229 of conducting material pivotally mounted on the handle body 261 at one end and having an inertia mass 250 at the other end and also having intermediate its ends a

first or inner contact 231 extending from each side. On one side of the contact 231 and arm 229 an outer contact 232-1 is mounted in the compartment 225 opposite the inner contact 231, and on the other side of the contact 231 and arm 229 a second switch arm 230 is pivotally mounted at one end of the handle body 261 and has mounted on its other end an outer contact 232-2, opposite the inner contact 231.

10 The switch arm 230 is urged away from the arm 229 as by a tension spring 263 connecting the arm 230 with the handle body 261. A trigger arm 234 is pivotally mounted in a slot in the handle body 261 and includes a cam nose 236 abutting against the outer side of the switch arm 230.

15 On the housing 212 about the pivot bolt 260 and at the inside of the control handle 259, there is located a boss 264 of insulating material having mounted in its outer face three spaced conductor rings 265, 266, and 267, each having a different diameter and which are concentric with each other and with the pivot bolt 260, and the handle body 261 has mounted therein contact pins 268, 269, and 270 respectively having their 20 inner ends slidably contacting the conductor rings 265, 266, and 267.

25 A conductor 271 connects the switch arm 230 which is of conducting material with the contact pin 268. A conductor 272 connects the switch arm 229 with the contact pin 269 and a conductor 273 connects the contact 232-1 with the contact pin 270.

30 A power supply cable 274 includes two conductors 275 and 276 adapted for connection at one end with a usual power supply line, and the conductor 275 is connected at its other end with the conductor ring 266. The conductor 276 at its other end is connected with one terminal of each of the solenoid coils 224-1 and 224-2. The other terminal of the solenoid coil 224-1 is connected with the conductor ring 267, and the other terminal of the solenoid coil 224-2 is connected with the conductor ring 265.

35 In the operation of the electric impact and interrupter switch apparatus 210, the trigger arm 234 is pulled against the switch arm 230 to effect an initial connection of the contact 232-2 with the inner contact 231 on the swinging or vibrating arm 229 causing an energization of the solenoid coil 224-2 and impact of the plunger arm 220 directly or indirectly against the sleeve anvil member 213-2, jarring the arm 229 40 away from the arm 230 and connecting the inner contact 231 with the other outer contact 232-1, and thereby energizing the other solenoid coil 224-1 and causing a reverse stroke of the plunger hammer 220 to impact against the anvil member 213-1 and jar the arm 229 and contact 231 away from the contact 232-1. The arm 229

45 thus vibrates to connect and disconnect the contact 231 successively with the contacts 232-2 and 232-1 to alternately energize the solenoid coils 224-2 and 224-1, reciprocate the plunger hammer 220, and cause successive impacts there- 50 of directly or indirectly against the anvil members 213-2 and 213-1, the frequency of which may be varied by operation of the trigger arm 234 to vary the spacing of the contact 232-2 from the contact 232-1.

55 In each of the switch arm and contact means 26, 126, and 226, gravity operating on the inertia masses of the vibrating arms thereof is relied upon to urge the vibrating arms to their equilibrium positions with respect to their mounting frames, and these vibrating arms are thus pen-

dulum arms which require that their pivoting axes be above their inertia masses.

In Fig. 8 a fourth embodiment of the invention is indicated generally by 310 and is an electric hammer or more broadly an electric impact and interrupter switch apparatus, which is generally similar with respect to its plunger and solenoid coils with the apparatus 210, and which includes a handle 358 mounting improved trigger controlled switch arm and contact means indicated generally by 326 which are generally similar to the trigger controlled switch arm and contact means 226, but which also include a tension spring 377 connecting the outer end of the vibrating switch arm 329 with the handle 358, whereby the electric hammer apparatus 310 is operative regardless of the position of the vibrating arm 329.

In Fig. 9 is illustrated a fifth embodiment of the invention in the form of a remote control variable frequency impact and interrupter switch apparatus indicated generally by 410 and which includes in a frame 411 operating parts substantially the same as the operating parts of the toy machine gun 110 without the cap tape feed means, and with the addition of a second switch arm and contact means 426-2 operative by vibration of the frame 411 to successively energize and de-energize a second electric circuit including conductors 478 and 479, as for example a circuit which may energize the solenoid coil of a remote heavy electric hammer, electric machine gun and the like.

The embodiments of the present invention illustrated and described herein are by way of example, and the scope of the present invention is not limited to the same or to the particular details thereof but is commensurate with any and all novel subject matter contained herein which may at any time properly under the United States patent laws be set forth in the claims hereof or originating herein, and the elements of any such claims are intended to include their functional or structural equivalents.

I claim:

1. In variable frequency electric impact and interrupter switch apparatus, a frame, electrically operated oscillating impact means for vibrating the frame, switch means on the frame for controlling the operation of the oscillating impact means, the switch means including a first spring arm and a second spring arm spaced at one side of the first spring arm, means mounting similar ends of the spring arms on the frame, each spring arm having an equilibrium position with respect to the frame, a first contact on the first spring arm and a second contact on the second spring arm opposite the first contact, the first spring arm vibrating from and to its equilibrium position with respect to the frame by vibration of the frame, and a member operative for swinging the second arm from its equilibrium position towards and away from the equilibrium position of the first spring arm for connecting and disconnecting the contacts and for varying the frequency of the oscillating impact means and the vibrating first spring arm and first contact.

2. In variable frequency electric impact and interrupter switch apparatus, a frame, electrically operated oscillating impact means for vibrating the frame, switch means on the frame for controlling the operation of the oscillating impact means, the switch means including a first spring arm and a second spring arm spaced at one

side of the first spring arm, means mounting similar ends of the spring arms on the frame, each spring arm having an equilibrium position with respect to the frame, a first contact on the first spring arm and a second contact on the second spring arm opposite the first contact, the first spring arm vibrating from and to its equilibrium position with respect to the frame by vibration of the frame, and a member operative for swinging the second arm from its equilibrium position towards and away from the equilibrium position of the first spring arm for connecting and disconnecting the contacts and for varying the frequency of the oscillating impact means and the vibrating first spring arm and first contact, and an inertia mass on the first spring arm.

3. In variable frequency electric impact and interrupter switch apparatus, a frame, electrically operated oscillating impact means for vibrating the frame, switch means on the frame for controlling the operation of the oscillating impact means, the switch means including a first arm and a second arm spaced at one side of the first arm, means mounting the first arm for swinging about an axis on the frame, and means mounting the second arm for swinging about an axis on the frame, a first contact on the first arm and a second contact on the second arm opposite the first contact, the first arm vibrating about its axis from and to an equilibrium position with respect to the frame by vibration of the frame, and a member operative for swinging the second arm towards and away from the equilibrium position of the first arm for connecting and disconnecting the contacts and for varying the frequency of the oscillating impact means and the vibrating first arm and first contact, and means urging the first arm towards its equilibrium position.

4. In variable frequency electric impact and interrupter switch apparatus, a frame, electrically operated oscillating impact means for vibrating the frame, switch means on the frame for controlling the operation of the oscillating impact means, the switch means including a first spring arm and a second spring arm spaced at one side of the first spring arm, means mounting similar ends of the spring arms on the frame, each spring arm having an equilibrium position with respect to the frame, a first contact on the first spring arm and a second contact on the second spring arm opposite the first contact, the first spring arm vibrating from and to its equilibrium position with respect to the frame by vibration of the frame, and a member operative for swinging the second arm from its equilibrium position towards and away from the equilibrium position of the first spring arm for connecting and disconnecting the contacts and for varying the frequency of the oscillating impact means and the vibrating first spring arm and first contact, and means urging the first spring arm towards its equilibrium position.

5. In variable frequency electric impact and interrupter switch apparatus, a frame, electrically operated oscillating impact means for vibrating the frame, switch means on the frame for controlling the operation of the oscillating impact means, the switch means including a first arm and a second arm spaced at one side of the first arm, means mounting the first arm for swinging about an axis on the frame, and means mounting the second arm for swinging about an axis on the frame, a first contact on

the first arm and a second contact on the second arm opposite the first contact, the first arm vibrating about its pivot axis from and to an equilibrium position with respect to the frame by vibration of the frame, and a member operative for swinging the second arm towards and away from the equilibrium position of the first arm for connecting and disconnecting the contacts and for varying the frequency of the oscillating impact means and the vibrating first arm and first contact, and spring means urging the first arm towards its equilibrium position.

6. In variable frequency electric impact and interrupter switch apparatus, a frame, electrically operated oscillating impact means for vibrating the frame, switch means on the frame for controlling the operation of the oscillating impact means, the switch means including a first arm and a second arm spaced at one side of the first arm, means mounting the first arm for swinging about an axis on the frame, and means mounting the second arm for swinging about an axis on the frame, a first contact on the first arm and a second contact on the second arm opposite the first contact, the first arm vibrating about its axis from and to an equilibrium position with respect to the frame by vibration of the frame, and a member operative for swinging the second arm towards and away from the equilibrium position of the first arm for connecting and disconnecting the contacts and for varying the frequency of the oscillating impact means and the vibrating first arm and first contact, and an inertia mass on the first arm, and spring means urging the first arm towards its equilibrium position.

7. In controlled frequency electric impact and interrupter switch apparatus, a frame, controlled frequency means including an oscillating member for subjecting the frame to vibration by successive impacts, a plurality of switch means on the frame each adapted for interrupting the current in an electric circuit in accordance with the frequency of the impacts against the frame, each switch means including two adjacent contacts, and means operatively mounting one of the contacts for vibration from and to connection with the other contact by vibration of the frame.

8. In controlled frequency electric interrupter switch apparatus, a frame, two spaced spring arms, means mounting each arm for swinging about an axis on the frame towards and away from the other arm, a contact on each arm opposite the contact on the other arm, and control means including a member adjacent one of the arms and operable to move the adjacent arm with respect to the other arm, the arm moving member being offset from the contact of the adjacent arm in the longitudinal direction of the adjacent arm.

9. In controlled frequency electric interrupter

switch apparatus, a frame, two spaced spring arms, means mounting each arm for swinging about an axis on the frame towards and away from the other arm, a contact on each arm opposite the contact on the other arm, and lever actuated control means including a member adjacent one of the arms and operable to move the adjacent arm with respect to the other arm, the arm moving member being offset from the contact of the adjacent arm in the longitudinal direction of the adjacent arm.

5. In controlled frequency electric interrupter switch apparatus, a frame, two spaced arms, means mounting each arm for free swinging about an axis on the frame towards and away from the other arm, a contact on each arm opposite the contact on the other arm, and lever actuated control means including a member adjacent one of the arms and operable to move the adjacent arm with respect to the other arm, the arm moving member being offset from the contact of the adjacent arm in the longitudinal direction of the adjacent arm.

10. In controlled frequency electric interrupter switch apparatus, a frame, two spaced arms, means mounting each arm for free swinging about an axis on the frame towards and away from the other arm, a contact on each arm opposite the contact on the other arm, and control means including a member adjacent one of the arms and operable to move the adjacent arm with respect to the other arm, and means urging the arm moving member away from the adjacent arm.

11. In controlled frequency electric interrupter switch apparatus, a frame, two spaced arms, means mounting each arm for free swinging about an axis on the frame towards and away from the other arm, a contact on each arm opposite the contact on the other arm, and control means including a member adjacent one of the arms and operable to move the adjacent arm with respect to the other arm, and means for vibrating the frame.

12. In controlled frequency electric interrupter switch apparatus, a frame, two spaced arms, means mounting each arm for free swinging about an axis on the frame towards and away from the other arm, a contact on each arm opposite the contact on the other arm, and means for vibrating the frame.

13. In controlled frequency electric interrupter switch apparatus, a frame, two spaced arms, means mounting each arm for free swinging about an axis on the frame towards and away from the other arm, and a contact on each arm opposite the contact on the other arm, and lever means including a member adjacent one of the arms swingable to move the adjacent arm with respect to the other arm.

14. In electric interrupter apparatus, a frame, two spaced arms, means mounting each arm for swinging about an axis on the frame towards and away from the other arm, a contact on each arm opposite the contact on the other arm, and means for vibrating the frame including solenoid series connected with the arm contacts and with a source of alternating current, a plunger operatively associated with the solenoid for movement into the solenoid when the solenoid is energized, an anvil opposite one end of the plunger, and means urging the plunger towards the anvil.
